UNITED STATES PATENT OFFICE.

HUBERT L. SHULER, OF ORANGEBURG, SOUTH CAROLINA.

CIGAR AND CIGARETTE HOLDER.

Application filed August 16, 1926. Serial No. 129,539.

This invention relates to a holder for cigars and cigarettes, the general object of the invention being to provide the holder with means for separating the moisture from the smoke as it passes through the holder so that nicotine and other liquids will not be introduced into the mouth of the user.

Another object of the invention is to so arrange the holder that the filtering means can be easily renewed when necessary.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a longitudinal sectional view through the improved holder.

Figure 2 is a section on line 2—2 of Figure 1.

Figure 3 is a view of the partition disk.

Figure 4 is a view of one of the filtering coils.

As shown in these views, the holder is composed of the two sections 1 and 2 which are threaded together, the mouthpiece section 1 being formed with a socket 3 therein which is closed by the section 2 which is shaped to receive the cigar or cigarette. A disk 4 having a central hole 5 therein is placed in the socket 3 and divides the same into two chambers. A coil 5' is inserted in each chamber, said coil comprising absorbent material 6 held on a core 7 of wire or the like. This coil may be composed of the pipe cleaning devices now on the market.

From the foregoing, it will be seen that the smoke passing through the two chambers will have any moisture therein taken from it by the absorbent material of the coils, the partition also acting to prevent moisture from passing from one chamber to the other. This partition also causes the smoke to circulate in the first chamber so that it will come in better contact with the first coil. Thus there is but little moisture in the smoke when it reaches the second chamber and this remaining moisture is taken up by the second coil. The smoke will reach the mouth of the user dry and practically free of nicotine. As will be seen, by separating the sections, the coils can be taken out and new ones substituted.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

A holder for cigars or cigarettes comprising a mouthpiece section having a reduced exteriorly threaded end with a chamber opening out through said end, a second section having a socket in its inner end threaded to receive the threaded portion of the first section, said second section closing the chamber, said second section having a passage therein communicating with the chamber and having its mouth enlarged to receive a cigar or cigarette, a partition in the chamber dividing the same into two parts and having a central opening therein and a coil in each chamber composed of absorbent material placed on a wire coil.

In testimony whereof I affix my signature.

HUBERT L. SHULER.
